(57) **CLAIM**

The ornamental design for a vehicle wheel, toy vehicle wheel, and/or replicas thereof as shown and described.

DESCRIPTION

This application contains subject matter related to the following co-pending U.S. design patent applications:
Application Ser. No. 29/858,122, filed Oct. 28, 2022 and entitled “Vehicle Wheel, Toy Vehicle Wheel, and/or Replicas Thereof;” and

Application Ser. No. 29/957,907, filed Aug. 16, 2024 and entitled “Vehicle Wheel, Toy Vehicle Wheel, and/or Replicas Thereof.”

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front elevation view thereof; and,

FIG. 5 is a side elevation view thereof.

1 Claim, 5 Drawing Sheets
